UNITED STATES PATENT OFFICE.

ROBERT HENRY KLINGEL, OF BRIDGEPORT, CONNECTICUT, ASSIGNOR TO
THE HOLMES & EDWARDS SILVER COMPANY, OF SAME PLACE.

DESIGN FOR A HANDLE FOR SPOONS, FORKS, &c.

SPECIFICATION forming part of Design No. 18,675, dated October 9, 1888.

Application filed June 16, 1888. Serial No. 277,378. Term of patent 14 years.

To all whom it may concern:

Be it known that I, ROBERT HENRY KLINGEL, a citizen of the United States, residing at Bridgeport, Fairfield county, State of Connecticut, have invented a certain new and original Design for Handles for Spoons, Forks, and other Articles of Table-Ware, of which the following is a full, clear, and exact specification.

The handle is adapted for spoons, forks, and other articles of table-ware, and the stem *a* of the handle is ornamented by a longitudinal projection, *b*, representing a rope with a plain flat rib, *c*, at each side; and at the upper end of this projection *b* is a ribbed shield, *c*, with radiating projections *d* below, and five upwardly-extending projections, *e*, at an enlarged or widened portion, *h*, of the handle, between the stem *a* and the blade *f*. The blade *f* expands gradually from above the part *h*, and is slightly rounded at the end, so that the general outline of the handle is oar-shaped, with

an enlargement, *h*, at the center. The blade is ornamented by a diagonal scroll, *j*, near the top, and below the scroll by a foliated figure, *k*, and above the scroll by a foliated figure, *m*, the main member of which is spiral; and along the edge of the blade and part *h* extends a plain rib, *n*.

The leading features of the design are a rope-like projection, the scroll and foliated ornaments, and the intermediate shield.

I claim—

A design for handles for spoons, forks, and other articles of table-ware, substantially as herein shown and described.

In testimony whereof I have signed my name to this specification in the presence of two subscribing witnesses.

ROBERT HENRY KLINGEL.
